UNITED STATES PATENT OFFICE.

MAX B. PUPP, OF SOUDERTON, PENNSYLVANIA, ASSIGNOR OF ONE-HALF TO C. K. GOTWALS, OF SOUDERTON, PENNSYLVANIA.

FLYING MACHINE OF THE AEROPLANE TYPE.

Application filed December 12, 1927. Serial No. 239,556.

My invention consists of new and useful improvements in aeroplane flying machines of the heavier-than-air type. My flying machine is of novel construction designed for 5 landing on land or water and being equipped with a central air dome and gas compartments insuring great buoyancy to the machine while in the air, and greater safety when 10 landing. In the event of accident or motor trouble a gradual and safe descent is obtainable.

The main object of my invention is the production of a flying machine constructed of metal or other suitable materials, and having 15 means by which the operator shall have absolute control of said flying machine while traveling in the air or descending for the purpose of landing on land or water.

A further object is to provide buoyancy 20 gas compartments, and a flexible, folding air dome and means for raising the air dome when used for buoyancy purposes, or to be lowered in a folding position when the machine is traveling through the air.

A still further object is the construction 25 of a flying machine equipped with a combination of safety buoyancy devices and adapted to carry passengers or freight according to the capacity and character of the 30 said flying machine, providing a machine more safe, useful, and commercially desirable.

With the above and other objects in view as will more fully appear as the description 35 proceeds, it will be observed that this invention consists of novel construction, arrangements and combination of parts as herein-after fully described, illustrated and claimed; it is to be understood, however, that numerous changes may be made in the construction 40 of this invention, or the folding air dome, which is centrally attached to the upper portion of the flying machine without departing from the spirit and intent thereof.

I attain these objects by means of the construction, mechanism and equipment illustrated in the accompanying drawings in which—

Figure 1 represents a front elevation of my 50 flying machine.

Figure 2 represents a side elevation of said machine.

Figure 3 represents an enlarged cross sec-

tion through the dotted line $x-x$. See 55 Figure 2.

Figure 4 a top plan view of said machine, having the central flexible folding air dome removed.

Figure 5 a longitudinal section of said machine through the dotted line $y-y$. See 60 Figure 3.

Figure 6 an enlarged cross section of the upper wing through the dotted line $z-z$.

Figure 7 represents an enlarged perspective view of the folding air dome expanded and 65 detached from the machine.

Figure 8 a perspective view of said air dome in a downward folding position.

Figure 9 a front end plan view of the air dome showing means for raising and lowering 70 said dome.

Referring to the drawings, similar numerals refer to similar parts throughout the several views, it being understood that each side of my flying machine is constructed and 75 appears the same, and all operating means is within the reach and control of the operator, whose position is under the air dome and at the rear of the central main motor.

Numeral 1 designates a pair of oblong 80 metal tubes spaced apart, divided into three parts, and extending longitudinally the entire length of said flying machine; numeral 2 designates a tight partition floor; 2' a tight partition ceiling by means of which floor and 85 ceiling the oblong metal tubes are divided into three parts throughout their entire length; 2'' designates the machine framework rigidly attached to the inner sides of the oblong tubes upon and within the said frame work and the oblong tubes, the wings and all other equipment is mounted in their 90 respective positions; 3 landing wheels; 4 lower wings; 5 upper wing; 5' strengthening stay bolts; 6 gas chamber within the wings; 7 fuel tanks in the lower portion of the oblong tube compartment; 8 passenger cabins; 9 gas chambers in the upper portion of the oblong tubes; 10 passenger seats; 11 cabin passageways; 12 central motor; 13 central propeller; 100 14 motors mounted on the top of the lower wings; 14' propellers; 15 vertical steering rudders; 16 steering arms attached to the vertical rudders; 16' tie rod between and connecting the vertical rudders; 17 side rudders; 105 18 steering arms attached to side rudders;

- 19 wire lines extending from side rudders to the operator's room; 19' wire lines extending from the vertical rudders to the operator's room, by means of which rudders and wire lines the operator regulates the direction of the flying machine, causing it to turn to the right or left and to ascend or descend while the machine is in motion; 20 operator's room; 21 operator's seat; 22 air dome chamber; 23 air dome bow frames; 24 flexible canvas constituting the air dome within and attached to the bow frames 23; 25 a shaft extending longitudinally through the center of said machine, and at the lower part of the air dome; 26 a plurality of spools on said shaft; 27 hand wheel mounted on said shaft; 28 sheaves; 29 wire connection at the lower end of the bow frames; 30 wires attached at the lower end of the bow frames and extending upward upon sheaves 28, and extending and attached to the spools 26, and by means of hand wheel 27 the air dome can be raised or lowered at the will of the operator; 31 steps at the door of the cabin entrance; 32 entrance door; 33 cabin windows.

It will be observed that in the construction of this improved flying machine I employ two oblong metal tubes, spaced apart and rigidly attached to the spacing framework in vertical position. The lower part of said tubes is of shape similar to the bottom of a boat. It is water tight and air tight, and constitutes the fuel tank designated 7. The central portion of said oblong tubes constitute passenger cabins, designated 8. The upper portion of said oblong tubes constitute buoyancy gas chambers, designated as 9. See Figure 3.

It will be observed further that the lower wings are rigidly attached to the outer sides of said oblong tubes, and the upper wing is rigidly attached to the inner side of said tubes, and further attached to the upper portion of the lower wings; said wings being spaced apart as shown in the different views.

It will be still further observed that this flying machine is equipped with an air dome which covers the entire space between the oblong tubes, and extends longitudinally nearly the entire length thereof, and when expanded extends to the upper wing, and when closed downwardly it rests on the frame brackets in a folding position as shown by the dotted lines, Figures 1, 3 and 9. It is to be understood that this air dome frame is lined with air tight, flexible canvas, and is raised and lowered by means of hand wheel 27, mounted upon shaft 25, and by means of wire connections therefrom, as shown in Figures 3 and 9. The operator has full control in the raising and lowering of said air dome, which when in the expanded position adds great buoyancy to a flying machine, especially when descending.

It will be observed still further that by inflating the upper chambers 9 of the oblong

tubes, and the inflating of the wing chambers 6 with gas, helium preferred, a still greater buoyancy is obtained.

I am aware that gas inflating means and air domes have been used in other flying machines; these I do not claim, as it will be observed that my methods and character of construction in obtaining buoyancy and safety means differs from the means employed in other flying machines.

From the foregoing description of construction and operation, my improved flying machine is fully illustrated in the accompanying drawings, illustrating what I believe to be the preferred embodiment of my invention, it being understood that the invention is not limited thereto, but that various changes may be made in the construction, proportions and arrangement of parts, without departing from the scope of my invention, as defined in the appended claims.

Having described my invention what I claim as new and desire to secure by Letters Patent is:—

1. A flying machine of the character described, consisting of two oblong tubes spaced apart, being rigidly attached to the sides of a central framework, the lower portion of said oblong tubes being in shape like unto a boat, and adapted for fuel tanks, a central passenger cabin within said oblong tubes adapted for carrying passengers, an upper chamber within said oblong tubes adapted to retain gas for buoyancy purposes, wings spaced apart and rigidly attached to the sides and extending crosswise over the longitudinal oblong tubes, chambers within said wings adapted to retain gas for buoyancy purposes, and motor means for propelling said flying machine as shown and described.

2. A flying machine of the character described, consisting of two oblong tubes spaced apart, being rigidly attached to the sides of a central framework, the lower portion of said oblong tubes being in shape like unto a boat and adapted for fuel tanks, a central passenger cabin within said oblong tubes adapted for carrying passengers, an upper chamber within said oblong tubes adapted to retain gas for buoyancy purposes, wings spaced apart and rigidly attached to the sides and extending crosswise over the longitudinal oblong tubes, a central folding air dome mounted upon the framework and extending longitudinally between the oblong tubes for buoyancy purposes and means for raising and lowering said dome as shown, and for the purposes set forth.

3. The combination in a flying machine, including two oblong tubes spaced apart by framework, each divided into three parts, providing fuel tanks, passenger cabin and gas buoyancy chamber, a plurality of wings attached to and extending crosswise of said ob-

long tubes, chambers within said wings adapted to retain gas for buoyancy purposes, a central folding air dome mounted on the framework and means for lowering and raising said dome for buoyancy purposes, a plurality of steering rudders attached to the rear end of the longitudinal tubes, and means for operating said rudders for steering purposes and motor means for propelling said flying machine substantially as described and for the purposes set forth.

In testimony whereof, I hereunto affix my signature.

MAX B. PUPP.
